UNITED STATES PATENT OFFICE

152,431

DESIGN FOR A BOTTLE

Jacob Payne, New York, N. Y.

Application September 12, 1947, Serial No. 141,347

Term of patent 7 years

(Cl. D58—9)

To all whom it may concern:

Be it known that I, Jacob Payne, a citizen of Great Britain and resident of the Borough of Manhattan, city, county, and State of New York, have invented a new, original, and ornamental Design for a Bottle, of which the following is a specification, reference being had to the accompanying drawing, forming a part thereof, wherein:

Fig. 1 is a front elevational view of a bottle showing my new design;

Fig. 2 is a side elevational view thereof;

Fig. 3 is a top plan view thereof; and

Fig. 4 is a bottom plan view thereof.

I claim:

The ornamental design for a bottle, substantially as shown.

JACOB PAYNE.
